UNITED STATES PATENT OFFICE.

ISRAEL LARSON, OF SANDY, UTAH.

TOOL-HOLDER.

No. 927,362.

Specification of Letters Patent.

Patented July 6, 1909.

Application filed April 16, 1908. Serial No. 427,371.

To all whom it may concern:

Be it known that I, ISRAEL LARSON, a citizen of the United States, residing at Sandy, in the county of Salt Lake and State of Utah, have invented certain new and useful Improvements in Tool-Holders, of which the following is a specification.

My invention relates to improvements in tool holders, and has for its object the provision of a combination tool holder which may be used for a number of different purposes and which will be thoroughly practical and desirable.

Another object of my invention is the provision of a combination tool holder which may be used as a complete device of itself or may be used in connection with a ratchet brace such as the one upon which patent was granted to me February 4, 1908, No. 878,404.

Another and further object of the invention is to provide a tool holder particularly useful for boring, driving screws and working in small or cramped spaces, and which may be used simply as a straight handle to hold the tool or as a ratchet device to actuate the tool.

A final object of the invention is the provision of a device of the character described which shall be of simple and durable construction and which shall be efficient for the purposes intended.

With these and other objects in view my invention comprises a holder having jaws at one end for gripping the shank of a tool and a removable cap on the opposite end of the holder, a bearing point received in the cap, and means in the body of the holder for gripping and holding tools of various sorts, the holder itself being adapted for connection with and to be used in connection with a ratchet brace.

The invention further consists of a combination tool holder embodying certain other novel features of construction, combination and arrangement of parts substantially as disclosed herein and as illustrated in the accompanying drawings, in which:

Figure 1, is a side elevation of my improved tool holder as in use as a screw driver or like instrument. Fig. 2, is a longitudinal sectional view of the holder. Fig. 3, is a sectional view of the device as in use in connection with my improved ratchet brace (Patent No. 878,404) showing the application of the bearing point which is ordinarily carried in the holder. Fig. 4 is the

sectional detail showing the double ended pawl and its associated parts. Fig. 5 is a cross section of the line 55 in Fig. 2. Fig. 6 is a cross section of the line 66 in Fig. 2. Fig. 7 is a cross section of the line 77 on Fig. 2.

In the drawings: The numeral 1, designates the main or body portion of the holder having an enlarged cylindrical portion 2, at one end to form a portion of the surface or circumference of the handle and from such enlarged portion, this member is of reduced diameter to provide a shank 3, which shank portion is longitudinally slotted as at 4, from the enlarged portion clear to the end of the shank. The shank has a smooth cylindrical portion 5, next to the enlarged portion thereof upon which is rotatably held the sleeve 6, for operating the gripping jaws, this sleeve preferably having an octagonal outer surface as shown serving as a handhold for rotating the sleeve. The shank is threaded from the cylindrical portion outward to the end thereof as at 7, and a sleeve 8, is secured upon the cylindrical portion of the stock or shank, by means of the transversely arranged pin or screw 9, which sleeve is spaced from and extends outward over the threaded portion of the stock. A flat slide 10, is confined in the slot of the shank in rear of the transverse pin 9, and the edges of the slide are threaded as at 11, to be engaged by the internal screw threads 12, on the operating sleeve 6, so that by rotating the said sleeve the slide is moved longitudinally in the slot of the shank. The forward end of the slide is forked or bifurcated as at 13, to receive the inner ends of the clamping jaws 14, the pin 15, passing through the forked ends of the slide and the inner ends of the jaws to hold the parts together and cause the jaws to work in unison with the slide, and the jaws are held normally distended or open by means of the spring 16, which bears upon the inner ends of the jaws. An internally threaded sleeve 17, is engaged upon the threaded portion of the shank, the end of the sleeve being normally in line with the end of the shank and the screw threads of this sleeve are terminated short of the end thereof as at 18. The clamping jaws have the beveled surfaces 19, to be engaged by the plain internal end portion 18, of the sleeve 17, and it will be apparent that by rotating the operating sleeve the clamping jaws are opened or closed as

desired to hold the proper tool such as a screw driver, gimlet, bit or the like.

In order to adapt the holder for service as a plain auger handle, a square opening 20, is provided in the handle or enlarged portion of the shank and to clamp the tang of the auger when so inserted in said squared opening, a rearwardly projecting lug or extension 21, is carried by the slide which is notched as at 22, to engage and clamp the tang of the auger or other tool. The other main or body portion of the holder consists of the cylindrical member 23, having screw thread connection 24, with the enlarged portion of the shank member, the lock screw 25, serving to hold the respective members against accidental rotation. The handle member is provided with a transverse cylindrical seat or recess 26, in which is rotatably held the ratchet 27, which ratchet is provided with a squared socket 28, to receive the tang of a bit or like tool. A double ended pawl 29, is pivoted at 30, and is shifted to engage either end of the ratchet tool socket by means of the transversely arranged plungers or push buttons 31, extending out through opposite sides of the handle. The central portion of the ratchet tool socket is left plain in the form of an annular groove 32, so that the pawl will only engage the ratchet teeth at either end of the socket holder. Thus a ratchet tool holder is provided for operating a tool in cramped spaces, the ratchet being operable for rotating in either direction.

A hollow cap 33, is mounted on the end of the holder which serves as a receiver for the bearing point 34, the said bearing point being rotatably mounted on the screw threaded shank 35. This bearing point is used in the manner indicated in Fig. 3, the screw threaded shank being connected to the bit stock 36, as illustrated. The bearing point is held in the cap by means of the spring 37, having the inturned end 38, to engage in the annular recess 39, in the shank of the bearing point. This spring is normally out of engagement with the bearing point but is depressed into engagement with the point by means of the slide 40, which has a depending lug 41, riding on the spring. The slide is actuated by a thumb piece or button 42, held in the slot 43. When the slide is pushed forward to lock the point in the cap, the end of the slide projects into the seat 44, in the end of the member 23, to lock the parts against unscrewing.

It will thus be evident that the device may be used as in a plain T or auger handle, a ratchet tool holder, and by means of the clamping jaws the holder may be used in connection with various tools. The holder is also of importance for use in connection with my ratchet brace shown in my Patent No. 878,404. Where my brace is being used

in a cramped place and it is impossible or impractical to use the crank arm of the brace, the crank arm is removed, the bearing point engaged on the end of the bit stock as in Fig. 3, and the internally threaded sleeve 70 17, on the end of the shank is partially unscrewed until it projects beyond the end of the shank and is then turned to make screw engagement with the arm of the bit holder as will be seen in the figure referred to. 75 When so partially unscrewed the protective sleeve 8, prevents entrance of dust or any foreign matter to the screw threads on the shank. Instead of the conical bearing point, the "bearing plate" as shown in the patent 80 8 may be used, or the cap 33, may be used as a handhold as indicated in dotted lines in Fig. 3.

From the foregoing description taken in connection with the drawings, the many 85 advantages and general usefulness of my improved tool holder will be readily understood and appreciated, and it will be apparent that I have produced a device of this character which fully and satisfactorily 90 accomplishes all the objects herein aimed at.

I claim:

1. In a tool holder, a body portion with enlarged portion at one end and a shank of reduced diameter longitudinally slotted from 95 said enlarged portion to the end of the shank, a sleeve rotatively held upon the shank, gripping jaws, and a slide confined in the slot of the shank with its edge threaded and having threaded engagement with 100 said sleeve, the forward end of said slide bifurcated to receive the inner ends of said clamping jaws.

2. In a tool holder, a body portion with enlarged portion at one end and a shank of reduced diameter longitudinally slotted from 105 said enlarged portion to the end of the shank, a sleeve rotatively held upon the shank, gripping jaws, and slide confined in the slot of the shank with its edge threaded and having threaded engagement with said sleeve, the forward end of said slide bifurcated to receive the inner ends of said clamping jaws, a pin passed through the bifurcated end of the slide and the inner ends of 110 the jaws.

3. In a tool holder, a body portion with enlarged portion at one end and a shank of reduced diameter longitudinally slotted from 115 said enlarged portion to the end of the shank, a sleeve rotatively held upon the shank, gripping jaws, and slide confined in the slot of the shank with its edge threaded and having threaded engagement with 120 said sleeve, the forward end of said slide bifurcated to receive the inner ends of said clamping jaws, a pin passed through the bifurcated end of the slide and the inner ends of 125 the jaws, the spring interposed between the jaws for normally holding them 130

open, and an internally threaded sleeve on the threaded portion of the shank, the clamping jaws having beveled surfaces for engagement with the end portion of said sleeve.

4. In a tool holder, a body portion with an enlarged portion at one end and a shank of reduced diameter longitudinally slotted from said enlarged portion to the end of the shank, a sleeve rotatively held on the shank, gripping jaws, a slide confined in the slot of the shank with its edge threaded and having threaded engagement with said sleeve, the forward end of said slide being bifurcated to receive the inner ends of said clamping jaws, a pin passed through the bifur-

cated end of the slide and the inner end of the jaws, a spring interposed between the jaws for normally holding them open, an internally threaded sleeve on the threaded portion of the shank, the clamping jaws having beveled surfaces for engagement with the end portion of said sleeve, said sleeve having the plain internal end portion, and the end of the sleeve being normally in line with the end of the shank.

In testimony whereof I affix my signature, in presence of two witnesses.

ISRAEL LARSON.
